SETTING SYSTEM FOR WATCHES

Samuel Mathez, Brooklyn, N. Y.

Application April 8, 1931, Serial No. 528,557

21 Claims.

(Cl. 58—65)

The object of this invention is to remove the objectionable features of the time setting of wrist watches.

The setting system now in vogue has always been a source of trouble to both the user and the watchmaker. When an ordinary wrist watch is being set the pulling out and pushing back of the crown and stem causes a certain amount of particles of dust, threads or fibers to be gradually introduced into the delicate parts of the watch, and with the natural moisture on the human body, the setting mechanism soon becomes badly impaired and often completely ruined by rust and wear.

15 Pulling out the small crown of the wrist watch for time setting purposes is usually a tedious operation often resulting in the breaking of finger nails, mashing of finger tips, and the breaking of pieces of the setting mechanism. When the setting mechanism has been made to work easier there is the danger of the crown pulling out accidentally when caught by a thread in the sleeve. Some are also apt to forget to push back the crown after setting the watch. These difficulties as well as others are completely eliminated by this invention.

The setting of a modern wrist watch is obtained by a change of gear. According to this invention the change of gear may be produced by bending down the strap lugs on one side of the watch. One pair of these lugs is strongly hinged to allow it to rock downwardly about a quarter of a turn. These two lugs are securely fastened to a shaft which holds them together and which is provided with means such as cams, levers or pins for operating the clutch wheel to control it for winding or time setting. In the accompanying drawings two forms have been adopted. For those who desire to set the watch when on the wrist a strong locking device has been provided to hold the lugs in position while the watch is being set. For those who prefer to wind up and set their watch before it is placed on their wrist the movement of the clutch wheel from the time setting to the winding position is automatically effected so that the watch is never in danger of being left in the time setting position inadvertently or by accident.

Among the objects of this invention are the provision of means for controlling the winding and time setting operations of a watch without necessitating the pulling out or pushing in of the crown, and at the same time avoiding a crowded condition of detents and levers around the stem of the crown; means for locking the controlling mechanism in winding or time setting position;

means for automatically returning the controlling mechanism into winding position; and means in connection with the locking means for indicating to the user when the controlling means is adjusted for time setting.

Other objects of the invention will be apparent from the following description taken in connection with the drawings, in which

Fig. 1 is a top plan view of the case cup of an open-faced wrist watch with the bezel and dial removed to show the connection between the clutch wheel of the winding and time setting mechanisms and a pair of pivoted strap lugs, showing the clutch wheel in winding position;

Fig. 2 is a view similar to Fig. 1 showing the clutch wheel in time setting position;

Fig. 3 is a detail sectional view on the line 3—3 of Fig. 1 showing the connections between the strap lug shaft and the clutch wheel shifting and lug locking mechanisms;

Fig. 4 shows the ready removability of the watch movement from the case with movable strap lugs in the position they assume when the watch is strapped on the wrist of the user and the clutch wheel is set for winding;

Fig. 5 shows the strap lugs moved into position to control the clutch wheel for time setting;

Fig. 6 is a detail of the locking mechanism for the movable strap lugs, showing the strap lugs in normal position;

Fig. 7 is a view of the strap lugs and locking mechanism with the strap lugs in position to control the clutch wheel for a time setting operation;

Fig. 8 is a view similar to a portion of Fig. 1 showing a modified connection between the lug shaft and the clutch wheel;

Fig. 9 is a view similar to Fig. 8 showing a further modification of the mechanism between the clutch wheel and the lug shaft;

Fig. 10 is a view similar to Fig. 8 showing still another modification of the connection between the lug shaft and the clutch wheel and means for automatically moving the clutch wheel from time setting position into winding position;

Fig. 11 shows a modified form of automatic releasing mechanism for the clutch wheel;

Fig. 12 shows a modified construction in which the strap lugs are attached to the bezel; and

Fig. 13 shows a bottom plan view of the modification shown in Fig. 12.

The modification shown in Figs. 1 to 7 comprises a case 12 provided with a circular flange, or cup 13 for removably receiving the watch movement 14, as is clearly shown in Figs. 1 and 2.

and as indicated in Fig. 4. Projecting from one end of the case are the usual preferably elongated strap lugs 15 here shown as rigid, but which may be hinged if desired in which is mounted a strap 5 pin 16 to which one end of the strap 17 is secured, as shown in Figs. 4 and 5. The other end of the case is provided with movable, preferably pivoted, strap lugs 18 and 19 which support a strap pin 20 to which the other end of the strap 10 17 is suitably secured. The strap lug 18, preferably provided with a hub pivoted in a lug on the case, is secured preferably permanently to a lug shaft 21. The lug 19 is preferably detachably mounted on the shaft by a set screw indicated in 15 Fig. 1, and may be provided with an enlarged hub portion 22 which may also be secured to the shaft by a set screw.

As shown in Figs. 1, 2, 3, 6 and 7, the shaft 21 may be provided with a cam lug 23 which cooperates 20 with a cam lug 24 on a locking spring 25 secured to the cup 13, as shown in Figs. 1 and 2. When the strap lugs 18 and 19 are in the position shown in Figs. 1, 3, 4 and 6 they are held and locked in this position by the engagement of the 25 cam lug 23 with the cam lug 24 as shown in Figs. 3 and 6. When the strap lugs are in the position shown in Figs. 2, 5 and 7, the cam lugs 23 and 24 cooperate as shown in Fig. 7 to hold the strap lugs 18 and 19 in the position shown in Figs. 2, 5 and 7.

As indicated in Figs. 3 and 4, the strap pin 20 is positioned close to the lug shaft 21 so that the strap may be fairly tight on the wrist of the user and still permit movement of the strap lugs 18 and 19 from the position shown in Fig. 4 to that shown 30 in Fig. 5, and also so that the pull of the strap on the strap lugs 18 and 19 will assist the locking spring 25 in holding the strap lugs in time setting position, as shown in Fig. 5, and prevent movement of the strap lugs into the winding position 40 shown in Fig. 4.

Fig. 1 shows the clutch wheel in the winding position, and Fig. 2 shows the clutch wheel in the time setting position. The crown 26 is provided with the usual stem 27 on which is loosely mounted the winding pinion 28 by means of which the 45 spring of the watch is wound. The portion of the stem 27 beyond the winding pinion is preferably square in cross section, as usual, for driving the clutch wheel 29 (also called sliding pinion) which in the position shown in Fig. 1 engages the clutch teeth on the winding pinion 28 and in the position shown in Fig. 2 engages on its other end with the intermediate wheel 30 which through a well known mechanism drives the hands of the watch 50 during time setting operations. As shown in Figs. 1 and 2, a clutch spring 31 normally tends to move the clutch wheel 29 into the winding position. 55

The clutch wheel shifting mechanism for shifting the clutch wheel from the winding to the time setting position comprises a setting lever 32 suitably pivoted on the upper plate of the movement of the watch, preferably in the position shown. The forward end of the arm 33 of the lever 32 60 engages a groove in the clutch. The intermediate portion of the arm 33 is provided with a pin 34 which cooperates with a lock spring 35 to hold the setting lever 32 in either of the positions shown in Figs. 1 and 2.

Comparing the construction shown in Figs. 1 to 7 with the old "pull out" system, it will be readily appreciated that the whole setting mechanism is more evenly distributed in this construction, part of it being in the case and part on the 75 movement. The usual detent and detent spring

crowded about the stem at the extreme edge of the watch are herein eliminated, thereby avoiding a lot of the trouble heretofore had with these elements.

The case may be of the usual construction comprising a cup case and a bezel. The case of this invention differs from the ordinary case in that one pair of lugs is preferably pivoted on a strong bearing in the case, the oblong, rectangular or tonneau shape being adopted to obtain the necessary space for the lug shaft and its bearings.

Heretofore the elongated lugs on the case were provided for the sake of appearance as they gracefully followed the lines of the case and strap and avoided the abrupt appearance of the short lugs. The elongated lugs are desirable in the present construction as they firmly rest on the wrist when pivoted downwardly in time setting position and thus assist the locking spring in holding the controlling mechanism as the watch is being set. The pressure of the lugs on the wrist, without being painful, is sufficient to remind the user that the mechanism is set for a time setting operation. This removes the danger of leaving the mechanism in time setting position after the time has been set. The strap pin should be located close to the lug shaft to avoid a material increase in the tension of the strap when the mechanism is in time setting position.

It is important that the shifting of the clutch wheel into time setting position should occur toward the end of the downwardly pivoting movement of the strap lugs. The movement of the strap lugs necessary to shift the clutch wheel has been made short by means of the arrangement of the setting levers on the watch movement so that the greater part of the movement of the strap lugs may be idle.

The other arm 36 of the setting lever 32 may be shaped as shown in Figs. 1 and 2 to cooperate with an impulse or driving pin 37 as well as with a release pin 38 on the lug shaft 21.

In the normal position of the strap lugs on the wrist of the user the lever 32 is in the position shown in Fig. 1, and the clutch wheel is held in engagement with the winding pinion 28 so that the watch may be wound by turning the crown 26. When the strap lugs are moved into the position shown in Figs. 2, 5 and 7, the pin 37 cooperates with the arm 36 of the lever 32 to move the lever 32 into the position shown in Fig. 2 which causes disengagement of the teeth of the clutch wheel 29 from the teeth on the winding pinion 28 and causes the gear teeth on the clutch wheel to engage with the setting pinion 30. 50 When the strap lugs are returned to the position shown in Fig. 1 the pin 38 rocks the lever 32 to move the clutch wheel 29 into engagement with the winding pinion 28. The locking spring 25 functions to hold the lug shaft and strap lugs 60 and the mechanism controlled thereby in each of the two positions. When it is desired to set the watch, the strap lugs are moved from the position shown in Fig. 4 to the position shown in Fig. 5 in which they are held by the lock spring 25. After the time setting operation has been performed the engagement of the ends of the strap lugs 18 and 19 with the wrist of the user tends to warn the user that the clutch wheel is shifted for time setting.

In the mechanism shown in Fig. 8, the lug shaft 21 is provided with a cam lug 23 cooperating with the cam lug 24 on the lock spring 25 which in this case may be on the right hand side of the case. The lug shaft 21 is provided with

- 5 a cam 48 which cooperates with a spring 41 which carries a pin 41a to transmit movement from the lug shaft to a lever 42 pivoted on the watch movement which in turn cooperates with a gear shifting lever 43 also pivoted on the watch movement to move the clutch wheel 28 from the winding position shown in Fig. 8 to its time setting position, as the strap lugs 18 and 19 are pivoted downwardly as shown in Figs. 2, 5 and 7.
- 10 The clutch wheel is normally urged into its winding position by means of a setting spring 44.

In the modified form shown in Fig. 9, the lug shaft 21 is provided with a pin 45 which engages in a slot 70 in a sliding setting bar 46 provided 15 with a slot 71 to receive a screw 72 threaded into the top plate of the watch movement. The forward end of the sliding bar 46 is guided by a pin 73 in said top plate and is provided with a cam portion 47 which cooperates with a cam portion 20 48 on a clutch spring 49 normally urging the clutch wheel 29 into the winding position shown in Fig. 9. As the strap lugs 18 and 19 are rocked into the position shown in Figs. 2, 5 and 7 the cooperating action of the cam portions 47 and 48 causes the clutch spring 49 to be flexed to the left to disengage the clutch teeth of the clutch wheel from the clutch teeth on the winding pinion and engage the gear teeth on the clutch wheel with the setting pinion.

30 In the modification shown in Fig. 10 the shaft 21 is provided with a pin 51 cooperating with a setting lever 32a somewhat similar to the construction shown in Fig. 1. The lever 32a is normally held in the position shown in Fig. 10 in which the clutch wheel connects with the winding pinion, by means of a spring 50 engaging the lever 32a in the manner shown.

The shaft 21 is also provided with a pin 51 which engages and flexes the spring 52 when the 40 strap lugs 18 and 19 are moved from the normal position shown in Fig. 1 to the position shown in Fig. 2. The function of the spring 52 is to automatically return the strap lugs 18 and 19 from the position shown in Fig. 2 to the position shown in Fig. 1 when operating pressure is removed from the strap lugs.

As shown in Fig. 11 a spring 53 coiled about the lug shaft 21 suitably anchored to the lug shaft and to the case 12 may be substituted for the 50 spring 52 shown in Fig. 10.

Watches provided with setting mechanisms for which lock springs are provided as shown in Figs. 1 to 9 may be controlled for time setting and then controlled for winding, while on the wrist of the 55 wearer, by one hand of the wearer. Watches provided with release springs as in Figs. 10 and 11 are controlled for time setting upon operation of the strap lugs by one hand and effecting time setting by the other hand. After the time has 60 been set, the pressure on the strap lugs is removed, thereby permitting the automatic restoration of the strap lugs and setting levers and clutch wheels.

In the modified construction shown in Figs. 65 12 and 13, the bezel 60 is provided with a pair of integral strap lugs 61 and 62 and a pair of pivoted strap lugs 63 and 64 and the cup case 65 may be hinged to the bezel as shown, one side wall of the 70 bezel being cut away as at 66 to receive the stem of the watch when the movement is pivoted into position in the bezel. Any suitable snap device may be provided to hold the cup case in position on the bezel. As indicated in Fig. 13 the pins operating the clutch wheel are located on the

underside of the lug shaft 67 which corresponds to the lug shaft 21 of the other figures.

As is obvious from the disclosure, the watch movement and levers and springs carried thereby may be readily removed from the cup case when the bezel is removed as in the modifications in Figs. 1 to 11 or when the cup case is pivoted away from the bezel in the modification in Figs. 12 and 13 as shown in Fig. 12. It is obvious that the case may be manufactured as a separate 10 article and that the watch movement may also be manufactured as a separate article, and that in accordance with my invention the case and movement may be readily assembled.

As indicated more particularly in Figs. 1, 2, 8, 15 9 and 10, the usual crowded condition of mechanism about the stem is avoided and the levers and springs are mounted so as not to interfere with the escapement mechanism and the usual trains 20 of gear mechanisms in the watch movement.

While the invention has been described with reference to several modifications disclosed, it is to be understood that still other embodiments may be made within the spirit of this invention and that the claims are not to be limited by the 25 disclosure except as necessitated by the state of the art.

What I claim is:

1. A wrist watch case comprising a main body portion for receiving a watch movement including time setting mechanism and a normally idle shiftable device for operating said mechanism, means for securing a strap to one end of said case, and strap lugs movably mounted in the other end of the case adapted upon movement to shift said device into cooperative engagement with the time setting mechanism.

2. A wrist watch case adapted to receive a watch movement including time setting mechanism and a normally idle shiftable device for operating said mechanism, a pair of fixed strap lugs at one end of the case, and a pair of movable strap lugs at the other end of the case adapted upon movement to shift said device into cooperative engagement with the time setting mechanism.

3. A watch case comprising a member for receiving a watch movement including time setting mechanism and a normally idle shiftable device for operating said mechanism, a bezel, means pivotally mounting said member on said bezel, a 50 pair of strap lugs rigid with one end of said bezel, and a pair of strap lugs pivoted on the other end of said bezel adapted upon movement to shift said device into cooperative engagement with the time setting mechanism.

4. The combination with a watch case comprising two members one of which is adapted to receive a watch movement and the other of which constitutes a bezel, said watch movement including time setting mechanism and a normally idle 60 shiftable device for operating said mechanism and pivoted strap lugs secured to one of said members and adapted upon movement to shift said device into cooperative engagement with the time setting mechanism.

5. In a wrist watch comprising a case housing a watch movement including winding and time setting mechanisms selectively operable through a shiftable clutch mechanism from any suitable driving means, a member mounted movably on the case and adapted to bear against the wrist of the wearer in its moved position, and operative connections between the movable member and the clutch mechanism for moving the latter to 70

connect the driving means with the time setting mechanism.

6. In a wrist watch comprising a case housing a watch movement including winding and time setting mechanisms operable through a shiftable clutch mechanism from any suitable driving means, a member mounted movably on the case and adapted to bear against the wrist of the wearer in its moved position, and operative connections between the movable member and the clutch mechanism for moving the latter to connect the driving means with the time setting mechanism, the connection between said member and the case permitting the movable member to be moved into a position in which the pull of the strap will tend to hold said member in moved position.

7. In a wrist watch comprising a case housing a watch movement including winding and time setting mechanisms operable through shiftable clutch mechanism from any suitable driving means, a member mounted movably on the case and adapted to bear against the wrist of the wearer in its moved position, operative connections between the movable member and the clutch mechanism for moving the latter to connect the driving means with the time setting mechanism, and means for locking said member in its moved position.

8. In a wrist watch comprising a case housing a watch movement including winding and time setting mechanisms operable through shiftable clutch mechanism from any suitable driving means, a member mounted movably on the case and adapted to bear against the wrist of the wearer in its moved position, operative connections between the movable member and the clutch mechanism for moving the latter to connect the driving means with the time setting mechanism, and means for holding said member in its normal moved positions.

9. In a wrist watch comprising a case housing a watch movement including winding and time setting mechanisms operable through shiftable clutch mechanism from any suitable driving means, a member mounted movably on the case and adapted to bear against the wrist of the wearer in its moved position, operative connections between the movable member and the clutch mechanism for moving the latter to connect the driving means with the time setting mechanism, and means automatically operating to move said member into its home position upon withdrawal of pressure applied thereto in moving it out of its home position.

10. In a wrist watch comprising a case enclosing a watch movement comprising winding and time setting mechanisms operable through a shiftable clutch wheel from the usual crown located outside of the case, a pair of strap lugs, a shaft on which said strap lugs are fixed, bearings on said case for said shaft, and connections between said shaft and clutch wheel for moving said clutch wheel into cooperative engagement with said time setting mechanism as said lugs are pivoted on said case.

11. In a wrist watch comprising a case enclosing a watch movement comprising winding and time setting mechanisms operable through a shiftable clutch wheel from the usual crown located outside of the case, a pair of strap lugs, a shaft on which said strap lugs are fixed, bearings on said case for said shaft, a setting lever pivoted on said watch movement and engaging said clutch

wheel, and means on said shaft for operating said lever.

12. In a wrist watch comprising a case enclosing a watch movement comprising winding and time setting mechanisms operable through a shiftable clutch wheel from the usual crown located outside of the case, a pair of strap lugs, a shaft on which said strap lugs are fixed, bearings on said case for said shaft, a lever pivoted on said watch movement having one of its ends engaging said clutch wheel, a cam portion on the other end of said lever, and a pin on said shaft for engaging with said cam portion on said lever, the construction being such that this engagement takes place toward the end of the pivoting movement of said strap lugs.

13. In a wrist watch comprising a case enclosing a watch movement comprising winding and time setting mechanisms operable through a shiftable clutch wheel from the usual crown located outside of the case, a pair of strap lugs, a shaft on which said strap lugs are fixed, bearings on said case for said shaft, a lever pivoted on said watch movement having one of its ends engaging said clutch wheel, a cam portion on the other end of said lever, a pin on said shaft for engaging with said cam portion on said lever, the construction being such that this engagement takes place toward the end of the pivoting movement of said strap lugs, a lock spring for said shaft mounted on said case, and a cam on said shaft cooperating with said spring for locking said strap lugs and shaft in the position in which the clutch wheel is controlled for time setting operations.

14. In a wrist watch comprising a case enclosing a watch movement comprising winding and time setting mechanisms operable through a shiftable clutch wheel from the usual crown located outside of the case, a pair of strap lugs, a shaft on which said strap lugs are fixed, bearings on said case for said shaft, a lever pivoted on said watch movement having one of its ends engaging said clutch wheel, a cam portion on the other end of said lever, a pin on said shaft for engaging with said cam portion on said lever, the construction being such that this engagement takes place toward the end of the pivoting movement of said lugs, a lock spring for said shaft mounted on said case, a cam on said shaft cooperating with said spring for locking said strap lugs and shaft in the position in which the clutch wheel is controlled for time setting operations, and means on said shaft cooperating with said lever for controlling the movement of said clutch wheel into engagement with the winding mechanism.

15. In a wrist watch comprising a case enclosing a watch movement comprising winding and time setting mechanisms operable through a shiftable clutch wheel from the usual crown located outside of the case, a pair of strap lugs, a shaft on which said strap lugs are fixed, bearings on said case for said shaft, a lever pivoted on said watch movement having one of its ends engaging said clutch wheel, a cam portion on the other end of said lever, a pin on said shaft for engaging with said cam portion on said lever, the construction being such that this engagement takes place toward the end of the pivoting movement of said lugs, a lock spring for said shaft mounted on said case, a cam on said shaft for locking said strap lugs and shaft in the position in which the clutch wheel is controlled for time setting operations, means on said shaft cooperat-

ing with said lever for controlling the movement of said clutch wheel into engagement with the winding mechanism, and a spring mounted on said watch movement normally urging said clutch wheel into position to engage said winding mechanism.

16. In a wrist watch comprising a case enclosing a watch movement including winding and time setting mechanisms operable through a shiftable clutch wheel from the usual crown located outside of the case, a pair of fixed strap lugs at one end of the case, a pair of strap lugs pivotally mounted on the other end of the case, and a connection between said pivoted strap lugs and said shiftable clutch wheel for moving the clutch wheel into driving engagement with the time setting mechanism upon pivotal movement of said strap lugs.

17. In a wrist watch comprising a case enclosing a watch movement including winding and time setting mechanisms operable through a shiftable clutch wheel from the usual crown located outside of the case, a pair of fixed strap lugs at one end of the case, a pair of elongated strap lugs pivoted on the other end of the case, an operative connection between said strap lugs and said clutch wheel for moving said clutch wheel into time setting position upon movement of said strap lugs out of normal position, and a strap pin carried by said movable strap lugs positioned closer to the pivot point of said strap lugs than to the free end of the strap lugs, the pivot connection between the strap lugs and the case being such that the lugs may be pivoted so that their longitudinal central plane may be moved through and beyond a plane substantially perpendicular to the case directed through the pivot points of said strap lugs.

18. In a wrist watch comprising a case enclosing a watch movement including winding and time setting mechanisms operable through any usual clutch mechanism from any desired driving means, means for securing a strap to one end of the case, a pair of strap lugs pivoted on

the other end of the case, means operable upon movement of said pivoted strap lugs for shifting said clutch mechanism for driving the time setting mechanism, and automatic means for returning said pivoted strap lugs into their normal home position upon removing pressure applied thereto for shifting the clutch mechanism into time setting position.

19. In a wrist watch movement carrying a crown to project from the side of a case provided with a pivoted strap holder, time setting and winding mechanisms, a shiftable clutch wheel for operating either of said mechanisms, a clutch wheel lever pivoted on said watch movement and having one of its ends operatively associated with said clutch wheel and having its other end projecting beyond said watch movement, and a member on said strap holder and cooperating with said projecting end of said lever.

20. In a wrist watch movement carrying a crown to project from the side of a case provided with a pair of pivoted strap securing lugs, time setting and winding mechanisms, a shiftable clutch wheel for operating either of said mechanisms, a clutch wheel lever pivoted on said watch movement and having one of its ends operatively associated with said clutch wheel and having its other end projecting beyond said watch movement in position to lie between and be operated by said securing lugs when the watch movement is in position in said case, and means associated with said lugs for cooperation with said other end of said lever.

21. A wrist watch case comprising a main body portion for receiving a watch movement including winding and time setting mechanisms and a shiftable device for operating said mechanisms, strap lugs movably mounted on said case, and means operated by said strap lugs for operating said shiftable device upon movement of said strap lugs to shift said device into cooperative engagement with either of said mechanisms.

SAMUEL MATHEZ.
